Murdant & Kilgore

UNITED STATES PATENT OFFICE.

HARRY C. RIDLER, OF MINNEAPOLIS, MINNESOTA.

HUMIDIFIER.

Application filed March 19, 1926. Serial No. 95,903.

My invention provides a simple and efficient humidifier for application to steam and hot water radiators and, generally stated, consists of the novel devices, combinations of 5 devices and arrangement of parts hereinafter described and defined in the claims.

The humidifier includes a spraying nozzle that is constructed to throw a very thin fan-shaped water or vapor film in a plane parallel and adjacent to one side of the radiator; and this spraying nozzle is associated with an upright shield that operates as a splash board and is connected at its bottom to a drip pan.

15 The shield is preferably located just back of the radiator or between the radiator and the wall and the vapor film is projected in the space between the shield and the back of the radiator. The above and other minor 20 but important features will appear in the following description of the invention as illustrated in the drawings.

Referring to the drawings wherein like characters indicate like parts throughout the 25 several views,

Fig. 1 is a front elevation view showing an ordinary steam or hot water radiator, the circulating pipes thereto and therefrom and the valves therefor not being shown;

30 Fig. 2 is a vertical section taken on the line 2—2 of Fig. 1;

Fig. 3 is a perspective showing the shield and drip pan removed from working position;

35 Fig. 4 is a detail partly in elevation and partly in axial section showing a filtering device interposed in the water supply pipe to the spraying nozzle;

40 Fig. 5 is a detail view partly in front elevation and partly in axial section showing the spraying nozzle and coupling to which it is attached;

Fig. 6 is a detail in section on the line 6—6 of Fig. 5;

45 Figs. 7, 8 and 9 are detail views in elevation illustrating progressive steps in the making of the spraying nozzle; and

50 Fig. 10 is a fragmentary elevation illustrating a plural arrangement of spraying nozzles.

The numeral 10 indicates an ordinary steam or hot water radiator made up of sections connected in the customary way and as usual mounted adjacent to a wall A. Arranged just back of the radiator and between the same and the wall is an upright shield 11

preferably of sheet metal formed with upright side flanges 12 and with a flanged upper portion 13. In the preferred arrangement, this shield is, at its lower portion, fitted into a drip pan 14, and it will be noted that the side flanges 12 are fitted against the end flanges 14^a of said drip pan.

By reference to Fig. 1, it will be seen that the drip pan and shield are slightly shorter 65 than the radiator so that the pan will pass between the longitudinally spaced legs of the radiator and the side flanges 12 will align with spaces between the extreme end and adjacent radiator sections. By reference to 70 Fig. 2, it will be noted that the drip pan is so set that it underlies most of the radiator and that the vertical flanges 12 will project slightly into the spaces between the radiator sections, thereby producing an overlapping 75 of said flanges 12 with the radiator sections. The drip pan 14 is shown as provided with a drain pipe 15 to carry off surplus water.

The nozzle employed for producing the very thin fan-like spray of water is so located that the vapor spray thereof will be projected in a vertical plane in the space directly between the shield and the radiator. This nozzle is formed with an externally threaded tubular shank 16 and with a head 80 85 17, which latter has a very narrow diametrical discharge passage 18. The nozzle may be supported in various different ways and connected to any suitable source of water supply under pressure. As shown, its threaded shank 16 is screwed into the upturned nipple of a T-coupling 19 into the opposite ends of which horizontal coupling pipe sections 20 and 21 are fitted. The outer end of the pipe 21 is closed by a cap 22. The extended end 90 95 of the pipe 20 is connected to the casing of a valve 23 that receives water from a suitable source under pressure such as the city water main connection, through a pipe 24.

The discharge passage 18 of the nozzle is 100 so thin that it might be plugged by even quite small objects carried in the water and, hence, to remove such objects from the water, I preferably use a filter. This filter, as shown, is afforded by a filtering material 25 105 contained in a tube 26 that is interposed in the pipe 20, and is connected thereto by a reducing coupling 27 and by a pipe union 28.

This discharge passage 18 is primarily formed by sawing a slit 18^a through the head 110 115 110 as best shown in Fig. 7. This slit 18^a will be formed by a very thin saw. Then

the slit head is pressed together, as shown in Fig. 8, and then the extreme sides of the head are closed by solder 18^b, as best shown in Figs. 5 and 9. The thickness of the slit 5 18^a and the formed discharge passage 18 is much exaggerated in the drawings. In fact, the discharge passage 18 is so extremely thin, (less than that of ordinary writing paper), that the spray of water discharged therefrom in the angle between the radiating arrows marked on Fig. 1 will be in the form 10 of a mist. This mist-like thin fan-shaped spray will be projected primarily in the space between the radiator and the shield 15 and will be stopped by the vertical flanges 12, but some of the mist will be lodged on the radiator, and the latter, being hot, will increase the rate of evaporation. The hot air in the space between the radiator and 20 shield will, of course, move upward, and as the water spray is projected in an upward direction and is of mist-like form, the evaporation will be rapid and the vapor will be carried upward and into the room. The 25 rate of evaporation is increased to a maximum and the precipitation of the water into the drip pan will be decreased to a minimum by the fact that the spray is projected upwardly and into the upwardly moving hot 30 air current. With the flanges 12 interlapped with the sections of the radiator, no space is left through which any part of the spray can be projected directly out of the space between the radiator and shield and hence 35 the water discharged from the nozzle must either be evaporated and carried upward with the air current or be precipitated onto the drip pan.

The efficiency of this humidifier has been 40 demonstrated in practice. It has been the common fault with humidifiers hitherto provided that they lack capacity to produce that kind of moisture that is required in a room or building heated by steam, water or 45 vapor. By means of the valve 23 the supply of water to the nozzle and hence the amount of water projected in a spray may be varied, and when the water delivery is set for a maximum the evaporation of water into the

air will be correspondingly increased to meet 50 any requirements. The humidifier has the further advantage that it may be readily applied to the radiator of any hot water, vapor or steam heating system, and is of low 55 cost.

By reference to Figs. 1, 2 and 3, it will be noted that the water supply pipe 20—21 is extended through the side flanges 12 of the shield 11 and is supported thereby, with the cap 22 and the valve casing 23 just outside 60 of the shield.

Fig. 10 illustrates a modified arrangement in which several of the spraying nozzles 17 are connected by T-couplings 29 to a supplemental water supply pipe 30, which, in 65 turn, is connected by a short pipe section 31 to the water supply pipe 20—21.

No claim is herein made to the specific form of operating nozzle, and so far as this invention is concerned, any suitable spraying nozzle may be employed.

What I claim is:

1. The combination with a radiator and an upright shield located adjacent to one side thereof, of a nozzle arranged to project a 75 spray upwardly in the space between said radiator and shield, and means for supplying water under pressure to the nozzle.

2. The combination with a radiator and an upright shield located adjacent to one side 80 thereof, of a nozzle arranged to project a spray upwardly in the space between said radiator and shield, means for supplying water under pressure to the nozzle, and a drip pan extending from the bottom of said 85 shield and under the radiator.

3. The structure defined in claim 2 in which said drip pan and shield are independently formed, but in which the former 90 fits within the latter.

4. The structure defined in claim 2 in which the shield has flanges and in which the means for supplying water to the nozzle under pressure includes a cross pipe seated 95 in the flanges of said shield.

In testimony whereof I affix my signature.

HARRY C. RIDLER.
